RACQUET PRESS

Alexander Alfred Allen, Burton-on-Trent, England

Application July 23, 1952, Serial No. 300,428

4 Claims. (Cl. 273—74)

This invention relates to racquet presses having two frames between which the racquet is intended to be held, the frames being connected together by studs or the like.

It is usual for these frames to be urged apart by spring means, and an operating device or devices is or are provided for compressing the frames together, against the spring action, to grip the racquet tightly.

The object of this invention is to provide a press which will be simple and inexpensive to manufacture and quick and easy to operate.

According to the present invention one end of each of the studs extends above the frame and is bent round to form a closed loop which is higher at one end nearer the centre of the press than at the other end nearer the outer edge of the press, the outer ends of operating levers being bent at right angles and located in these loops, so that when the press is opened by raising the levers their ends are in the higher ends of the loops, while when the levers are pressed down to close up the press, the ends of the levers move into the lower ends of the loops, where there is insufficient clearance to receive them, except by compressing the frames together against the spring action.

The parts are so proportioned that in the tightening movement the levers can move slightly beyond the dead centre position, so that their inner ends are in actual contact with the face of the press frame, and thus there is no tendency for them to open out again unless definitely operated.

The inner ends of the levers may be connected together by extending them parallel with each other across the press and enclosing them in a sheath to hold them together, so that the levers can be operated simultaneously by one movement.

The studs with their looped extensions and also the operating levers can all be formed out of stout wire or thin rod material, which is inexpensive and provides a simple manner of construction, since the same material can be used for both studs and levers.

The invention will now be described with reference to the accompanying drawings:

Figure 1 is a plan of the press.

Figure 2 is a side elevation.

Figure 3 is a section on the line III—III of Figure 1.

The press consists of two frames 10 each of the same four-cornered shape as seen in Figure 1, and the frames are secured together by a stud 11 at each corner. Each stud has a spring 12 fitted round it tending to urge the frames 10 apart. The upper ends of the studs (as viewed in the drawings) extend above the surface of the upper frame 10 and are bent round at 11a so that each part 11a forms a closed loop which is higher at the inner end than at the outer end, as can be clearly seen in Figure 3. Four operating levers 13, 14, 15, 16 are provided and their outer ends are bent at right angles as shown at 13a, 14a, 15a, and 16a, and are located within the looped parts 11a. When the press is open to allow a racquet to be inserted or withdrawn, that is to say when the levers 13, 14, 15, 16 are raised, as shown in dotted lines in Figure 2, the lever

ends 13a, 14a, 15a, 16a lie in the higher parts of the loops. When the levers are pressed down flat, and slightly beyond the dead centre or horizontal position, so that their inner ends are in actual contact with the face of the press frame, as shown in Figure 1 and in firm lines in Figure 2, the lever ends 13a, 14a, 15a, 16a move down the looped parts 11a into the outer ends of the loops, and in this movement they exert a leverage against the narrowing loop and force the press frames together, thus tightening up the frames to grip a racquet. A small plate 17 is fastened to the top face of the upper press frame at each corner and the studs 11 pass through the plates and are bent round and have their ends attached to or passed through the plates to close the loops 11a. The inner ends of each pair of levers are extended across the press parallel with each other and close together, as shown at 18, so that each pair of levers 13, 16 and 14, 15 consists of one length of stout wire or thin rod bent to the desired shape. The parallel parts 18 are enclosed within a sheath 19 to hold them together and serve as a handle; the sheath 19 is welded or otherwise fixed to one of the parts 18 and the other part 18 is free to rotate slightly in the sheath as the levers are operated. The studs have the usual adjusting nuts 20 on their opposite ends and the bottom frame 10 (as viewed in the drawings) is countersunk to allow these adjusting nuts to be flush. Obviously instead of the sheath 19 any suitable handle member could be attached to the levers.

I claim:

1. A racquet press comprising a pair of frames, said frames each being of quadrilateral four-cornered shape four studs connecting the frames together in spaced parallel relation said studs being located one near each of the four corners of the frames, a coil spring fitted round each stud, said springs bearing against said frames and tending to urge the frames apart, an end region on each stud said end region extending above the frame and being bent round to form a closed loop which is higher at the part of it which is nearer the centre of the press and tapers towards the part of it which is further away from the centre of the press, the loops on one side being oriented along a common line extending through the center of the studs on such side, and the loops on the other side being oriented along a common line extending through the center of the studs on said last named side, operating levers operatively connected with the press, such operative connection including bent end regions on said operating levers, said bent end regions being located one in each of said closed loops, said operating levers and said studs together with their end regions all being made of thin rod-like material, said levers being pivotally raisable from the press, in which position their bent ends are in the higher parts of the loops, said levers being also capable of being pressed down on to the press whereupon their bent ends move into the tapered parts of the loops, where there is insufficient clearance to receive them except by compressing the frames together against the spring action.

2. A racquet press as claimed in claim 1 in which the length of the levers is slightly greater than the distance between the studs spacers on the frame through each of which a stud passes so that when levers are pressed down on to the press they can move slightly beyond the dead center position so that they are in contact with one of the press frames and there is no tendency for them to open out again until definitely operated.

3. A racquet press as claimed in claim 1 having the levers formed in two pairs each pair consisting of a single length of material bent to shape so as to provide the two levers with their bent end regions and a straight connecting portion.

4. A racquet press as claimed in claim 1 having the levers formed in two pairs each pair consisting of a single length of material bent to shape so as to provide the two

levers with their bent end regions and a straight connecting portion, the two connecting portions being situated close alongside each other, and being operable together so that all four levers are operated simultaneously by means of these connecting portions.
